UNITED STATES PATENT OFFICE

2,202,028

PROCESS FOR PRODUCING HIGH-GRADE
ROSIN AND TURPENTINE

Joseph A. Scruggs, Pensacola, Fla.

Application January 18, 1938, Serial No. 185,593

2 Claims. (Cl. 202—46)

My invention relates to an improved process for producing high-grade rosin and turpentine.

The extraction of turpentine and pine oil from wood chips by the use of steam, with or without vacuum is now in common use. In processes heretofore employed, the rosin must be first produced by the solvent or other well-known methods, and is, thereafter, refined by chemical treatment or by distillation or by both methods combined. In the ordinary distillation process, the rosin is often injured by contact with hot metal when raised to the temperature necessary for distillation, and in some cases due to the presence of air.

Rosin has also been produced by the so-called "destructive distillation" processes, but it has been of an extremely low grade.

The ordinary retort produces a grade of rosin known as FF. Some producers then put the rosin through one or more additional processes to produce a higher grade of rosin. This additional process requires considerable time and the use of expensive machinery and formulae, which, consequently, add greatly to the cost and market price.

The following are among the objects of my present invention:

First, to produce a product of higher grade and at a greatly reduced production cost as compared with other processes hitherto and now in use, and to this end my improved product is produced by a single process without the necessity for further refining.

This present invention involves a new principle in the distillation of rosin directly from the wood chips, instead of destructive distillation in which the necessary excessive heat destroys the wood, but by my present improved process there is produced a high-grade rosin by means of the first operation as distinguished from other methods of manufacture in which a low grade rosin is first produced and thereafter refined by succeeding processes in order to raise the grade, thus in my process avoiding the added cost of further purification.

The four figures of the drawing illustrate four slightly varying apparatus in which my improved process may be carried out.

Referring to Fig. 1, A is a vessel in which chips of wood are placed. This is sealed tight. Heat is applied by means of steam entering through the steam pipe 1. After the chips are brought to a temperature in the neighborhood of 320° F., a valve 2 is opened and vacuum is applied by vacuum pump 3 through the condenser 4, and under these conditions spirits are distilled off. This cycle may be repeated if found necessary until the spirits are all distilled off, or steam may enter through the pipe 1 continuously to keep the chips hot.

Later, the valves 2 to the condenser 4 and the valve 5 in the steam-pipe are closed. The steam now in vessel A is circulated through the blower 6 and superheater 7 located immediately below vessel A, and then through the chips in vessel A continuously. Incidentally, the superheater 7 is preferably placed immediately beneath the vessel A, in order that the hot gas after passing around the superheater may be used to prevent radiation loss from vessel A.

This superheated steam thoroughly dries the chips. Excess steam generated from any moisture in the chips is drawn off through the condenser 4, vacuum being applied through the condenser by means of the vacuum pump 3 to remove the steam, after which the valve 2 to the condenser is closed.

At this point in the process, a liquid, for example gasoline or certain other hydrocarbon mixtures, is introduced through pipe 8 controlled by valve 9 therein, into the vessel A. This liquid passes through the blower 6, to the superheater 7 where it is vaporized. Sufficient liquid is pumped in to build up a pressure of about one hundred twenty-five (125) pounds to the square inch. Gas from the liquid is circulated through the superheater until the chips reach a temperature of about 520° F. A valve 10 in the pipe 11 leading to a condenser 12 is then opened and vacuum is applied by the vacuum pump 13 in connection with the condensers 12 and 14, and a filter and separator 15.

By means of this vacuum, the heat stored in the chips, and the action of the gas through the chips, the rosin is vaporized from the chips and passes immediately to condenser 12 where the rosin is condensed with part of the gas, and the balance of the gas passes to condenser 14, where it is condensed to be used again. The condensed rosin with its condensed gas first passes through a filter or separator 15 to a still 16.

The foregoing cycle is repeated until the rosin is entirely vaporized from the chips.

The liquid with the rosin in the still 16 is distilled off through the condenser 14 to a reservoir 18. The rosin may be drawn off directly from the bottom of the still 16 through a cock 19.

Referring now to the showing in Fig. 2, the same numerals have been employed up to and including 12 to corresponding parts, since the two apparatus are the same up to and including this point. In the form shown in Fig. 2, there are three rosin condensers 20, 21 and 22, in series with the idea of producing three grades of rosin, if desired. For each condenser, there is a separator, and these are numbered 23, 24 and 25, and a corresponding number of reservoirs 26, 27 and 28 are provided, that is to say there are a series of three rosin condensers, separators and reservoirs, all of which are supplied from the vessel 60

A through the pipe 11, pipes 30 leading from the rosin condensers to the separators, and pipes 31 leading from the separators to the condensers 21 and 22, and pipes 32 leading to the several 5 reservoirs 26, 27 and 28, and from these reservoirs, the rosin flows through the pipes 33, preferably to a common still 34, valves 70 being provided in each of these pipes to be used when required. From the still 34, a pipe 35 leads to 10 a condenser 36, and another pipe 37 may lead directly from the separator 25 to the condenser 36, and a vacuum pump 38 is connected with the pipe leading from the condenser 36 to the reservoir 39.

15 In the construction illustrated in Fig. 3, the letter A and the numerals 1, 2, 3, 4, 5, 6, 7, 8, 9, 10 and 11 are the same and represent the corresponding parts described in connection with Figs. 1 and 2, and hence are not repeated. In 20 this connection, the parts 3 and 4 are duplicated as 3a and 4a, thus providing separate condensers for spirits and pine oil, the numeral 4 representing the spirits condenser, and 4a the pine oil condenser.

25 The pipe 11 leads to a rosin condenser 40, and from the condenser 40 to a separator 41, and 42 represents a pump. A pipe 43 leads from the pump 42 to a continuous still 44. From the separator 41, a pipe 45 leads to a condenser 46, from 30 which latter one pipe 47 leads to the continuous still 44, and another pipe 48 to a vacuum pump 49, and thence to a reservoir 50.

In the construction shown in Fig. 4, a blower 51 is located in the pipe 11 between it and 35 the valve 10, and from the rosin condenser 52 a pipe 53 leads into another condenser 54, and from condenser 54 one pipe 55 leads to a condenser 56 and a vacuum pump 57 withdraws the rosin to a condenser 58, and from there it is 40 carried to a reservoir 59. The pipe 60 extends from the rosin condenser 54 to a continuous still 61, and a pipe 62 leads from this still to a condenser 63 from which the condensation is removed by a vacuum pump 64 to a reservoir 65. 45 A blower 51 is provided to accelerate the movement of the gas and vapor through these several condensers. The blower might be placed in the pipe 55 between the two condensers 54 and 56, if desired.

50 A blower might, of course, be used, if desired, with the previously described apparatus.

The superheated gas in my improved process imparts the heat necessary to the chips without the rosin coming in contact with metal and without overheating any part of the rosin as is frequently the case, as has been previously pointed out, when rosin is heated to the necessary temperature by ordinary methods of distillation.

55 My improved process uses a smaller quantity of gasoline or other hydrocarbons than is used by various solvents and processes.

The distilling off of the spirits and pine oil by steam may be done in cycles as has been described, or may be done continuously. The spirits and 60 pine oil are preferably distilled off before the superheated gas is circulated through the chips. In my improved process, the rosin as well as the spirits and pine oil are vaporized from the chips by means of a hot dry gas, thus leaving most of 65 the impurities and coloring matter in the chips.

70 As an illustration, the use of a blower permits the evaporation of a given weight of rosin, say with two hundred (200) gallons of gasoline. This two hundred gallons of gasoline is heated to the 75 vapor point, then the latent heat of evapora-

tion is applied to the two hundred gallons of gasoline, then the vapor therefrom is superheated to the desired degree and circulated through the chips by the blower, giving off some of the superheat to the chips. It is then circulated through the blower and superheater to replace the superheat given off to the chips. This cycle is repeated until the chips are brought to the desired temperature and until, by repeated applications, the latent heat of evaporation of 10 the rosin has been stored in the chips.

Without the use of the blower, eight thousand (8,000) gallons instead of two hundred (200) gallons of gasoline would be required for the evaporation of the same given weight of rosin. This 15 would represent a prohibitive cost due to the great quantity of heat required and the quantity of gasoline lost in the process because the eight thousand gallons of gasoline would have to be heated, first to the vapor point, then the latent 20 heat of evaporation applied to the eight thousand gallons of gasoline, and then the superheat to the desired degree. The same small percentage is lost in each case, say, for example, approximately 2%; however 2% of eight thousand (8,000) gallons is one hundred sixty (160) gallons, an excessive loss, whereas 2% of two hundred (200) gallons is only (4) gallons loss with the blower.

The rate of expansion of the superheated gas to the vacuum desired is so controlled that isothermal expansion is practically obtained. During evaporation of the rosin from the chips a small quantity of gas is fed through the superheater to pass off with the rosin vapor.

Finally, it may be stated that my improved 35 process does not destroy the wood which may be used later for fuel or any other purposes.

I claim:

1. A process of producing from particles of 40 coniferous wood, turpentine, pine oil and a purified and decolorized rosin, by placing a charge of said wood particles in a vessel, sealing the vessel, circulating the steam through the charge to remove the turpentine and pine oil, removing the residual moisture; then recycling through 45 the charge without condensation superheated hydrocarbon gas of the character of gasoline, which will not crack at the temperatures used, and which superheated gases increase the temperature of the charge to about 520° F.; then drawing from the vessel the hydrocarbon gases by application of vacuum, and then drawing off the purified and decolorized rosin by vacuum distillation induced by the stored heat.

2. A process of producing from particles of 55 coniferous wood, turpentine, pine oil and a purified and decolorized rosin, by placing a charge of said wood particles in a vessel, sealing the vessel, circulating the steam through the charge to remove the turpentine and pine oil, removing the residual moisture; then recycling through the charge without condensation superheated hydrocarbon gas of the character of gasoline, which will not crack at the temperatures used, and 60 which superheated gases increase the temperature of the charge to about 520° F.; then drawing from the vessel the hydrocarbon gases by application of vacuum, whereby the rosin is vaporized; and then drawing off the purified and 65 decolorized rosin by vacuum distillation induced by the stored heat, and separating the rosin from any remaining hydrocarbon by distilling the hydrocarbon off.
